(57) **CLAIM**

The ornamental design for postal indicia for an envelope, as shown and described.

DESCRIPTION

FIG. 1 is a top plan view of postal indicia for an envelope showing our new design, the broken lines of the envelope and stamp are not part of the claimed design;

FIG. 2 is an enlarged front elevational view thereof;

FIG. 3 is a top plan view of a second embodiment of postal indicia for an envelope showing my new design; and,

FIG. 4 is an enlarged front elevational view thereof.
